TERMINAL FORMING AND ATTACHING APPARATUS

Frank Martindell, Western Springs, Ill., assignor to Western Electric Company, Incorporated, New York, N. Y., a corporation of New York

Application November 16, 1938, Serial No. 240,724

4 Claims. (Cl. 153—2)

This invention relates to terminal forming and attaching apparatus and more particularly to an apparatus for forming terminals from strip material and attaching them to spool heads, which are later assembled on coils.

It is an object of the present invention to provide mechanism for expeditiously forming electric terminals and attaching them to their supports.

In accordance with one embodiment of the invention, relatively light metallic bands are fed from supply spools to a reciprocatory forming die which partially forms a terminal and advances it into association with a terminal support to which the terminal is to be fixed. Operating in timed relation to the feeding and partial forming mechanism are a set of staking and cutoff tools which stake the partially formed terminal on its support and hold it in that position during the partial forming of a new section of the strip, and thereafter complete the forming of the terminal and shear it from the strip.

A better understanding of the invention may be had by reference to the detailed description of the apparatus when considered in conjunction with the accompanying drawings, wherein

Fig. 1 is a side elevational view of the apparatus embodying the invention;

Fig. 2 is an end elevation, on an enlarged scale, of the apparatus shown in Fig. 1, looking at the right side of Fig. 1;

Fig. 3 is a plan view, on an enlarged scale, of the apparatus shown in Fig. 1, some of the parts being broken away to conserve space;

Fig. 4 is an enlarged partial plan view of the reciprocatory feeding and forming mechanism;

Fig. 5 is a sectional view taken on the line 5—5 of Fig. 4 in the direction of the arrows;

Figs. 6 and 7 are fragmentary sectional views, taken on the lines 6—6 and 7—7, respectively, of Fig. 5 in the direction of the arrows;

Fig. 8 is an enlarged fragmentary sectional view, taken on the line 8—8 of Fig. 2, showing the details of construction of the final forming dies;

Fig. 9 is a sectional view, taken substantially on the line 9—9 of Fig. 8 in the direction of the arrows;

Fig. 10 is a horizontal sectional view, taken on the line 10—10 of Fig. 8 in the direction of the arrows;

Fig. 11 is a fragmentary sectional view taken 55

on the line 11—11 of Fig. 10 in the direction of the arrows; and

Figs. 12 and 13 are plan and side elevational views, respectively, of a support in the form of 5 a spool head for an induction coil with terminals fixed thereto by the operation of the apparatus shown in the other views.

Referring to the drawings, wherein like reference characters designate the same parts 10 throughout the several views, the numeral 11 designates a base upon which the various parts of the mechanism are mounted. The base 11 supports a motor 12 and a single revolution clutch 13, which may be of any suitable type, since 15 the details thereof do not concern the present invention. The single revolution clutch is operated under control of a link and lever mechanism, designated generally by the numeral 14, connected to a suitable treadle, not shown, positioned beneath the base 11. Each time the clutch 13 is operated, it will drive a shaft 17 through one revolution and then automatically disengage.

The shaft 17 has a brake mechanism, designated generally by the numeral 175, associated therewith and comprising a pair of brake shoes 176 and 177 mounted upon an upright member 178 fixed to the base 11. The brake shoes 176 and 177 are urged into engagement with a brake drum 186, fixed to the shaft 17, by a pair of compression springs 179 and 180. The compression spring 179 surrounds the upright member 178 and is held in place thereon by a wing nut 181 threaded on the upper end of the member 30 178 and between which and the brake shoe 177 the spring is interposed. The left end of the brake shoe 176 has a threaded rod 182 fixed therein which extends through an aperture 183 in the brake shoe 177 and has a compression spring 180 surrounding it and interposed between the upper surface of the brake shoe 177 and a wing nut 185 threaded on the rod 182. By means of this mechanism, the brake shoes 35 176 and 177 are always exerting a braking action on the shaft 17, whereby the shaft will not overrun when the single revolution clutch is disengaged and the shaft 17 will therefore always stop in the same position.

Extending upwardly from the base 11 are a pair of bearing members 15 and 16, which rotatably support the drive shaft 17, which in turn carries a plurality of cams 18, 19, 20 and 21. Associated with the cam 18 is a cam roller 22 (Figs. 1 and 3) mounted intermediate the ends

of a cam lever 23, which is pivoted on the base 11 at 24. The cam lever 23 controls the operation of the feeding and partial forming apparatus, an arm 25 fixed to the lever 23 and having pivoted on its free end a pair of links 26 and 27 (Fig. 3) transmitting the motion from the cam 18 and lever 23 to the feeding and partial forming mechanism. Pivotally connected to the ends of the links 26 and 27 are a pair of slidable blocks 28 and 29, respectively, which are slidable on adjustable guide plates 30 and 31, respectively. The slidable blocks 28 and 29 and the guide plates 30 and 31 are of exactly the same construction and only one guide plate and slidable block will be described in detail, that is, the guide plate 31 and the slidable block 29, which are shown in detail in Figs. 4 and 5.

Extending upwardly from the base 11 are two projections 40 and 41, which support the guide plate 31. The projection 40 has a pair of mounting lugs 42 and 43 extending upwardly from it and the projection 41 has two lugs 44 and 45 extending upwardly from it. The lugs 42, 43 and 44 have threaded apertures 46, 47 and 48 for receiving set screws 49, 50 and 51, respectively, and the lug 45 receives the butt end of a headed screw 52. The headed screw 52 is threaded into a plate member 53, which, with a cooperating plate member 54, comprises the guide plate 31. The members 53 and 54 are accurately positioned with respect to one another by keys 55 and 56 set into the abutting portions of the members and are held in parallel relation by a pair of keys 57 and 58. The set screws 49, 50 and 51 and the headed screw 52 may be adjusted to accurately position the guide plate 31 with respect to the final forming mechanism.

The slidable block 29 is normally drawn to the right (Figs. 3, 4 and 5) by a spring 60 fixed to the projection 41 and connected to a pin 61 mounted in the slidable block 29. The lever 27 is pivotally connected to the slidable block 29 by means of a screw 62 threaded into the slidable block 29, a washer 63 being provided for spacing the lever 27 slightly away from the guide block.

Mounted upon the slidable block 29 are a tape gripping device and a tape forming device, designated generally by the numerals 64 and 65, respectively. The tape gripping device 64 comprises a pair of blocks 66 and 67 keyed together, as shown at 68, and bolted to the slidable block 29 by machine screws 69. The blocks 66 and 67 are cut away, as shown in Fig. 7, to provide a passageway 70 for the passage of the partially formed tape, designated 71, and to receive a gripping member 72, which has an enlarged portion 73 abutting a plate 74 fixed to the blocks 66 and 67. As will be noted in Fig. 4, the blocks 66 and 67 are not exactly rectangular in shape and the gripping member 72, which is slidable between the plates, is tapered so that when the slidable block 29 moves to the left (Figs. 4 and 5), the partially formed tape 71 will tend to hold the gripping member 72 and the block 29 may thus be freely moved to the left without moving the partially formed tape 71. However, when the block 29 is moved to the right, (Figs. 4 and 5) a spring 75, which normally urges the gripping member 72 to the left with respect to the block 29, will force the gripping member 72 into engagement with the tape and the shape of the tape and its retaining plate 74 will cause the gripping member 72 to grip the tape tightly and move it to the right (Figs. 4 and 5). The tapes 71 are thus drawn from a pair of reels 76 and 77 (Figs.

1 and 3), mounted on a common hub 78, by the gripping members 72 on the slidable blocks 28 and 29 each time the blocks are moved to the right (Figs. 3, 4 and 5).

5 The tapes 71 are directed to the tape-forming devices 65 by a pair of guide rollers 79 and 80 and during the movement of the slidable blocks 28 and 29 to the right (Fig. 3), the tape forming devices 65 will be inoperative. However, when 10 the cam 18 positively cams the arm 25 to the left against the action of springs 81 and 60, the spring 81, being fixed to the cam lever 23 and bearing 16, the tape, which will at that time have been gripped by other mechanism, to be described hereinafter in connection with the final forming of the terminals, will be held against movement to the left, and as the two slidable blocks 28 and 29 are cammed to the left, the tape forming devices 65, mounted thereon, will fold the tape into a U-shaped configuration.

20 The tape-forming devices 65, mounted on the slidable blocks 28 and 29, are of exactly the same construction and comprise a pair of forming blocks 90 and 91 keyed together, as shown at 92 (Fig. 6), and have a forming member 93 positioned between spaced-apart portions thereof. The forming blocks 90 and 91 have tapered slots 94 and 95 formed therein to provide forming surfaces for folding the tape 71 over the forming member 93, which is held in place between the blocks by a retaining plate 96. The tapered slots 94 and 95 gradually merge into a straight slot, which conforms substantially to the shape of the forming member 93, but is somewhat larger, so that as the forming device 65 is driven to the left by its actuating cam 18, it will fold the tape 71 around the forming member 93.

30 As just described, the tape will be formed into U-shaped configuration and fed to the final forming tools, which will now be described.

35 Two bolsters 110 and 111 extending upwardly from the base 11 cooperate with the projection 41 to support a die block 113, in which there is slidably mounted a spool head retaining member 114. The spool head retaining member 114 has pivoted to its lower end a cam lever 115, which is pivoted on a pin 116 extending into a bracket 117 mounted on the base 11 (Fig. 2). The cam lever 115 is normally urged upwardly by a spring 118 fixed to the lever and to a stud 119 formed on the bolster 111. A bolt 120, threaded into a portion of the bolster 111 and locked in place therein by a nut 121, serves to restrain the lever 115 from movement beyond a predetermined 50 point under the contractile action of the spring 118 so that the upward movement of the spool head retaining member 114 may be accurately regulated.

55 The cam lever 115 carries a cam roller 122 thereon which lies in the path of movement of the cam 19 and will be actuated by the cam 19 at a predetermined time in the cycle of operation of the machine. The cam 19 is so formed that the spool head retaining member 114 will be moved downwardly after terminals have been assembled on the spool head and completely cut from the tape 71. When a completed set of terminals have been fixed to a spool head, a spring 124, which cooperates with the spool head retaining member 114 to clamp a spool head thereon, will become effective to eject the spool head upon the lowering of the retaining member 114. This spring 124 is mounted in an aperture 125 in the die block 113 and will hold a spool head during the forming of the terminals and will eject the

spool head upon the retraction of the retaining member 114.

Also pivoted on the pin 116 is a lever 130 connected by a link 131 to a cam lever 132 (Fig. 2). Cam lever 132 is pivoted on a stud shaft 133, mounted on the bearing member 16, and carries on it a cam roller 134 positioned between the link 131 and the stud shaft 133. The lever 130 (Figs. 8 and 9) has a pin 135 fixed in it which engages in a slot 136 formed in a staking pin actuator 137. The staking pin actuator carries a pair of staking pins 138 and 139 which are slidable in apertures 140 and 141 formed in the die block 113. The left end (Fig. 2) of the cam lever 132 has pivoted thereon an adjustable push rod 142, to the lower end of which there is fixed a staking die 143 (Figs. 8 and 9) slidably positioned between a bridge 144 and a retaining plate 145. The staking die 143 has a pair of staking pins 146 and 147, which are in direct vertical alignment with the staking pins 138 and 139, and which cooperate with the staking pins 138 and 139 to stake the pair of terminals onto a slotted spool head with which the terminals have been assembled.

There is also mounted upon the stud shaft 133 a cam lever 150, which carries a cam roller 151 for cooperation with the cam 21. Fixed to one end of the cam lever 150 is a spring 152, which has its opposite end secured to the base 11 at 153 (Fig. 2) for normally urging the cam roller 151 into engagement with the cam 21. The end of the cam lever 150, away from the spring 152, has adjustably secured thereto a cutting die 155, which, at its lower end, is provided with a pair of shearing members 156 and 157, which cooperate with a pair of die cavities 158 and 159, respectively, formed in the die block 113 to shear the terminals from the tape 71. The terminals, as shown in Figs. 12 and 13, are sheared by the shearing members 156 and 157 along the lines 160, 161 and 162 after the terminals have been fed into slots 163 in a spool head 164 and staked thereon, as shown at 165-165, by the staking pins 138, 139, 146 and 147.

Mounted in a central aperture in the cutting die 155 is a crimping die 166, which is slidable upon a threaded member 167 and is normally urged downwardly by a compression spring 168 (Figs. 8 and 9) seated in a pocket 169 formed in the cutting die 155 and resting against the upper surface of the crimping die 166. Mounted closely adjacent the cutting dies 156 and 157 are guide members 170 and 171, respectively, which are of exactly the same construction, and comprise a block 172 (Fig. 11) and a spacer plate 173. The spacer plate 173 fits in between the folds in the folded tape 71 and acts as a shearing surface against which the cooperating cutting member 156 or 157 may shear the formed terminal from the supply of tape.

It is believed that a better understanding of the construction of the mechanism may be had from the following brief description of the mode of operation thereof.

After the motor 12 has been started in any suitable manner, an operator may insert a spool head 164 in the machine, placing it so that its central aperture surrounds the upper portion of the retaining member 114 and its left edge (Figs. 3 and 10) is engaging the spring 124, whereby the spool head will be retained in the apparatus with the slots 163 in the head thereof in alignment with the folded tape 71 to be fed thereto. As soon as the spool head has been placed

in this position, the treadle, not shown, may be operated to transmit motion through the link and lever mechanism 14 to the single revolution clutch 13 to set it in operation. This will cause the shaft 17 to rotate through one revolution, where it will be stopped by the brake mechanism 175. The shaft 17, in rotating through one revolution, will cause a partially formed section of tape 71 to be fed into the slots 163 in the spool heads 164. This is accomplished by the movement of the slideable blocks 28 and 29 to the right (Fig. 3) due to the cam roller 22 riding down the surface of the cam 18 under the action of the springs 60 and 61. In the drawings, particularly in Fig. 3, cam 18 has been shown in the position where the slideable blocks 28 and 29 have advanced sections of tape into the slots in the spool head and are almost back to the normal position. In the feeding of the tapes 71 into the slots in the spool head, the arm 25 and the cam lever 23 are drawn to the right by the springs 60 and 61 and will move the blocks 28 and 29 to the right. Blocks 28 and 29, in moving to the right, will feed the tape 71 due to the action of the tape gripping device 64, wherein gripping member 72 will be urged into engagement with the tape 71 by the spring 75 and as its associated block 28 or 29 will start to move to the right, will be wedged into the partially formed tape and will carry the tape to the right (Figs. 3, 4 and 5). After the partially formed tapes 71 have thus been fed to the slots 163 in the spool head, the cam 18 will positively drive the cam lever 23 and arm 25 to the left, and at the time that the cam 18 is driving the slideable blocks 28 and 29 to the left, the right end of the tapes 71 will be gripped by the staking and crimping mechanism so that it will be restrained against movement and the tape forming device 65 will move with respect to the tape, thereby forming the tape into U-shaped cross-section during the movement of the tape forming device to the left (Figs. 3, 4 and 5).

In Figs. 2 and 8 to 10, inclusive, the machine is shown in its rest position, that is, the position where no spool head has been placed on the retaining member 114, and all of the dies are in their inactive position. It will be understood, however, that while the slideable blocks 28 and 29 are in their extreme right-hand position, where the partially formed tapes are inserted in the slot 163 in the spool head, the cams 20 and 21 will become effective to simultaneously move their associated staking pins, crimping dies and shearing dies to a position to fix the partially formed tapes on the spool head and partially shear the terminals from the supply of tape. The cams 20 and 21 simultaneously move their associated parts to cause the staking pins 138, 139, 146 and 147 to stake the terminals to the spool head 164 and to cause the crimping dies 166 and the shearing members 156 and 157 to flatten the spaced-apart portions of the partially formed tape and to move them into engagement with one another. The shearing members 156 and 157, in moving to this position, will cooperate with the guide members 170 and 171 to shear the upper fold of the tape 71 and press it down against the lower fold. The cam 21 is so formed that it will move its shearing members 156 and 157 simultaneously with the movement of the staking pins 138, 139, 146 and 147 until the shearing members have cut through the top layer of the folded tape, as hereinbefore stated, and then both the staking pin actuator 137 and staking

die 143 and the shearing members 156 and 157 will dwell in that position while the cam 18 drives the slideable blocks 28 and 29 (Figs. 4 and 5) to partially form a new section of the tapes 11 and after the new sections of tapes have thus been partially formed, the cam 21 will further actuate the cutting die 155 to shear through the remainder of the tape. However, the crimping die 166 will not move with the shearing die 155, but will remain stationary and the threaded member 167 will move downwardly compressing spring 168, and after slideable blocks 28 and 29 have been moved to their extreme left-hand position by the cam 18, the staking die 143, staking pin actuator 131 and shearing die 155 will all be returned to their normal position, as shown in Figs. 8 and 9. Shortly after they have moved to their normal position, the cam 19 will become effective to move the spool head retaining member 114 downwardly, thereby permitting the spring 124 to flip the spool head with the formed terminals attached thereto out of the machine and the machine will then be in condition to receive a new spool head as soon as the shaft 17 comes to rest. In this position, the spool head retaining member will be returned to the position shown in Fig. 8.

Although a specific embodiment of the invention has been described hereinbefore, it will be understood that many modifications may be made in the described device without departing from the invention, which is to be limited only by the scope of the appended claims.

What is claimed is:

1. In an apparatus for forming terminals and attaching them to a support, a reciprocable block, a feeding and forming mechanism mounted on said block for feeding material to be made into terminals to the support during movement thereof in one direction and for forming the material to a predetermined configuration during movement thereof in the opposite direction, and means operable in timed relation to the operation of said feeding and forming mechanism for securing the fed material to the support, said securing means also serving to hold one end of the fed material during movement of the block in one direction.

2. In an apparatus for forming terminals and attaching them to a support, a reciprocable block, a feeding and forming mechanism mounted on

said block for feeding material to be made into terminals to the support during movement thereof in one direction and for forming the material to a predetermined configuration during movement thereof in the opposite direction, a staking member for fixing a terminal to its support, a crimping member for folding material to form the terminal, and a shearing member for cutting the terminal from a strip, said crimping member and staking member being operable to hold the strip from moving with the forming device during the forming movement of the forming device away from the crimping and staking members.

3. In an apparatus for forming terminals and attaching them to a support, a reciprocable block, a feeding and forming mechanism mounted on said block for feeding material to be made into terminals to the support during movement thereof in one direction and for forming the material to a predetermined configuration during movement thereof in the opposite direction, means operable in timed relation to the operation of said feeding and forming mechanism for securing the fed material to the support, and means in said securing means for holding one end of the fed material during the forming of said material by the feeding and forming mechanism.

4. In an apparatus for forming terminals and attaching them to a support, a reciprocable block, a feeding and forming mechanism mounted on said block for feeding material to be made into terminals to the support during movement thereof in one direction and for forming the material to a predetermined configuration during movement thereof in the opposite direction, a staking member for fixing a terminal to its support, a crimping member for folding material to form the terminal, and a shearing member for cutting the terminal from a strip, said shearing member being operable to first shear part of the said strip and later complete the shearing of the strip to form the terminal, said shearing means also being operable to hold the strip from moving with the forming device during forming movement of the forming device away from the shearing means.

FRANK MARTINDELL.
